(57) CLAIM

The ornamental design for a video storage tray, as shown and described.

DESCRIPTION

FIG. 1 is a perspective view of a video storage tray showing my new design;

FIG. 2 is a front view of the video storage tray shown in FIG. 1;

FIG. 3 is a right side view of the video storage tray shown in FIG. 1;

FIG. 4 is a left side view of the video storage tray shown in FIG. 1;

FIG. 5 is a back view of the video storage tray shown in FIG. 1;

FIG. 6 is a top view of the video storage tray shown in FIG. 1;

FIG. 7 is a bottom view of the video storage tray shown in FIG. 1; and,

FIG. 8 is a perspective view of the video storage tray in its extended configuration.

The broken lines are for illustrative purposes only and form no part of the claimed design.

1 Claim, 6 Drawing Sheets
